UNITED STATES PATENT OFFICE.

WILLIE HOLDSWORTH, OF PROVIDENCE, RHODE ISLAND.

FALLER-BAR.

1,329,904.

Specification of Letters Patent.

Patented Feb. 3, 1920.

Application filed December 18, 1918. Serial No. 267,391.

To all whom it may concern:

Be it known that I, WILLIE HOLDSWORTH, a subject of the King of England, having declared my intention of becoming a citizen 5 of the United States, residing at Providence, in the county of Providence and State of Rhode Island, have invented a new and useful Faller-Bar, of which the following is a specification.

10 This invention relates to a faller bar for use on gill drawing frames.

The principal objects of the invention are to provide a faller bar of this character which can be made by unskilled labor instead of the specialists now necessary and yet will be more durable than those heretofore made; which will have its pins so arranged that they cannot fall out in the only way in which they now fall out in practice, 20 that is through the back; which will be so constructed that the pins can be made of different construction than cylindrical, which is now the universal shape so that they will have greater strength; which will 25 be so made that the bar itself can be materially thicker so as to increase its strength; which will be cheaper because shorter pins can be used; and which can be repinned very easily either with pins of the same size 30 and shape or with different ones and different numbers to the inch, thus materially economizing in the first cost and particularly in the cost of maintenance.

Further objects and advantages of the invention will appear hereinafter.

Reference is to be had to the accompanying drawings in which—

Figure 1 is a plan of part of a gill drawing frame showing the faller or gill bar in 40 the position it assumes when it comes up between the end of the saddle and disk and illustrating it in connection with the gill bar frame which is the subject of the patent to William Holdsworth, No. 722,984;

45 Fig. 2 is a side elevation of the same showing the top and bottom screws with my improved faller bars in section;

Fig. 3 is a side view of my improved faller bar partly in section;

50 Fig. 4 is a sectional view on the line 4—4 of Fig. 3;

Fig. 5 is a plan of the same as indicated by the line 5—5 of Fig. 4, and

Fig. 6 is a transverse sectional view show-

ing a pair of pins in the act of being introduced.

For the purpose of illustration I have shown the invention as applied to the gill drawing frame illustrated in the above mentioned patent to William Holdsworth. But 60 it is to be understood that the invention is not limited to that particular type of drawing frame. The invention itself lies entirely in the faller bar and not in any novelty of its association with the rest of 65 the parts of the frame. This faller bar as will be understood from reference to the above mentioned patent is moved through a path of substantially rectangular form. It is moved longitudinally by the screws 1 70 and 5 raised by the cam 3 from the screw 1 up to the screw 5 and passes around the saddle 7 described, dropping by the cam at the end of the screw 5 that is not shown in Fig. 2.

These faller bars as heretofore constructed 75 are made by highly specialized mechanics who receive pay all out of proportion to the difficulty of their work and yet it is a trade that has to be learned by experience because the faller bars are bored to gage so 80 as to set the pins at the rate of twelve to sixteen per inch in a space eight or ten inches long. The pins are made of wire of such size that the holes into which they 85 are inserted are very close together and have to be drilled with care. These holes extend clear through the faller bars and in order 90 to avoid having the holes too long the faller bars have to be made of smaller cross section than is otherwise desirable. Consequently 95 they frequently break. Furthermore the pins drop out through the back during use thus necessitating their replacement at frequent intervals. These difficulties are all overcome by this invention as will appear. These advantages are secured in a very simple manner.

The faller bar 10 is made at the ends the same as it is now so that it can be guided in a proper manner as above mentioned, but 100 its shank is made of greater depth than has been the case heretofore and instead of boring through it to provide holes for the pins it is provided with a longitudinal groove or recess 11 in the upper side passing only 105 part way through it. For example in some cases this groove will be only $\frac{5}{8}$ ths or $\frac{3}{8}$ ths of an inch deep. The sides of this groove

and bottom are made plain. In this groove fits with a driving fit a locking bar 12. This locking bar is provided with parallel depressions 13 on its opposite sides. These are 5 made to fit the teeth or pins and provide the necessary spacing so as to bring the points of the pins at the desired distance apart throughout the length of the bar and the two sides of this locking bar are made 10 alike, except that where there is a space on one side preferably there is a projection between two spaces on the other directly opposite it. The pins are placed by hand in the several notches or depressions in the 15 locking bar and lean against the sides of the faller bar as indicated in Fig. 6 and then the locking bar 12 is driven in so as to force the pins to a perfectly straight and parallel position and firmly lock them in place.

20 It will be seen that the butts of the pins are considerably shorter than has been the case heretofore. Consequently there is a material saving in the amount of wire used.

Furthermore there is no possibility of the 25 pins coming out through the bottom as will be obvious.

In the old constructions the continual dropping of the faller bar on a solid surface tended to loosen the pins and they 30 always eventually began to come out at the bottom. This I avoid, thus reducing the expense of maintenance very materially. Furthermore the faller bar can be repinned very easily and in doing so it is not necessary to repin it with pins of the same size 35 or the same pitch. Merely by changing the locking bar 12 these elements can be changed accordingly. Furthermore the bar itself is much deeper and thicker than it has been 40 heretofore, and it is stronger so as to better withstand the usage to which it is put. The pins also do not have to be cylindrical at their butts but can be square, triangular or of any other desired shape to secure the 45 greatest strength.

When it is desired to take the pins out, ejectors are introduced in three perforations 15 extending from the bottom of the socket 11 to the bottom of the faller bar. They are 50 driven in to force out the faller bar 12.

Although I have illustrated and described only a single form of the invention and shown it as applied to a single form of drawing frame, I am aware of the fact that modifications can be made in it and the principle 55 can be applied to other types of drawing frames without departing from the scope of the invention as expressed in the claims. Therefore I do not wish to be limited to all 60 the details of construction or to the particu-

lar type of drawing frame herein shown and described, but what I do claim is:—

1. As an article of manufacture, a faller bar for a gill drawing frame having means removably located entirely in the front face 65 thereof for detachably fastening pins in position, and means for positively preventing pins from dropping out through the back.

2. As an article of manufacture, a faller bar for a gill drawing frame having a solid 70 bottom portion and a longitudinal groove in the top for receiving pins in position to abut against said solid bottom, and a locking bar arranged in said groove adapted to engage against the sides of the butts of the 75 pins and hold them firmly in position thereon.

3. As an article of manufacture, a faller bar for a gill drawing frame having a solid 80 bottom portion, a longitudinal groove in the top of said bar, and a locking bar arranged in said groove having notches along its surface fitting a series of pins and spacing them from each other for holding them firmly in position in the groove.

4. As an article of manufacture, a faller bar for a gill drawing frame having a solid bottom portion, a longitudinal groove in the top of said bar for receiving two rows of pins, and a locking bar arranged in said 90 groove adapted to engage against the butts of the pins and hold them firmly in position therein, said bar having notches on the two opposite sides thereof along its surface fitting the pins and spacing them from each 95 other.

5. As an article of manufacture, a faller bar for a gill drawing frame having a solid bottom portion, a longitudinal groove in the top of said bar for receiving the pins, and 100 means extending through the bar from below for ejecting the pins.

6. As an article of manufacture, a faller bar for a gill drawing frame having a row of pins detachably mounted therein, and 105 means for simultaneously locking all the pins in position in the bar.

7. The combination with a faller bar for a gill drawing frame and two rows of pins mounted therein, of means for simultaneously unlocking all the pins of both rows, said means being capable of releasing them.

8. A faller bar for a gill drawing frame having pins projecting therefrom, and means whereby said pins can be removed 115 and other pins placed in the same bar at different distances apart.

In testimony whereof I have hereunto affixed my signature.

WILLIE HOLDSWORTH.
